UNITED STATES PATENT OFFICE.

JOHN P. SUNDERLAND, OF ALBANY, NEW YORK, ASSIGNOR TO GEORGE G. MILNE, OF RYE, NEW YORK.

ELECTRIC HEATING APPARATUS.

1,304,626.

Specification of Letters Patent. Patented May 27, 1919.

Original application filed August 1, 1917, Serial No. 183,831. Divided and this application filed February 25, 1919. Serial No. 279,092.

To all whom it may concern:

Be it known that I, JOHN P. SUNDERLAND, a citizen of the United States, and a resident of Albany, in the county of Albany and State of New York, have invented certain new and useful Improvements in Electric Heating Apparatus, of which the following is a specification.

My invention relates to improvements in electric heating apparatus and is especially adapted to the heating of rivets, bolt blanks and other articles of iron, brass and the like, the ohmic resistance of which is relatively low when cold. This application is a division of my prior application Ser. No. 183,831 filed August 1st, 1917.

It has heretofore been suggested that rivets may be heated by passing an electric current therethrough but prior arrangements have been unsuccessful because of burning of the rivets. This burning of the rivet or other article is the local melting or liquefying of the rivet particularly at the end of the rivet. In my prior application Serial No. 247,480 filed July 31, 1918, I have described and claimed a method of preventing this burning by keeping the voltage within certain defined limits. When the rivet, bar or other article of iron or the like is placed in circuit with the secondary of a suitable transformer, the ohmic resistance of the article is relatively low because it is cold. Upon heating up its resistance increases, but when first put in circuit it practically short circuits the secondary as the term "short circuit" is commonly used. The main object of the present invention is to provide an improved system or apparatus which will keep down the voltage at the start so as to prevent the flow of excessive current which would cause burning of the rivet or other articles and which initial burning is often evidenced by a splattering of the molten metal.

Further and more specific objects, features and advantages will more clearly appear from the detailed description given below taken in connection with the accompanying drawings which illustrate an apparatus particularly adapted for heating rivets, bolt blanks and the like although with modifica-

tions it may be adapted to the heating of many other articles.

In the drawings, Figure 1 is a side view of the apparatus, 55

Fig. 2 is a plan view of the same, certain parts being omitted or broken away to more clearly illustrate others;

Fig. 3 is a front end view of the same, certain parts being omitted to more clearly 60 illustrate others;

Fig. 4 is a section on the line A—A of Fig. 2;

Fig. 5 is a section through the transformer, taken on the line B—B of Fig. 2; 65

Fig. 6 is a diagram illustrating diagrammatically the transformer connections and windings.

Referring to the various figures, 1 represents a base board on which is secured an insulating board or sheet of asbestos 2. Secured upon one end of the base is an electrical contact head of soft metal, such as copper, 3, extending along the front of the apparatus. Pivoted to the framework at 5 75 are two pairs of arms 4, in the ends of which are secured respectively, electrical contact heads of soft metal, such as copper, 6, the heads being insulated from the arms 4, which support them. Handles 7 are suitably secured to the arms 4, so that the heads 6 may be raised and lowered away from and toward the head 3 to permit the insertion of rivets 8 between the heads, with one end of each rivet abutting the head 3 and the other 85 end of each rivet abutting one of the heads 6.

9 represents a transformer, suitably secured to the base, and having bolted to the top thereof brackets 10, which may serve 90 as handles for the apparatus. The primary of the transformer consists of three sets of windings 14, 12 and 13, consisting of 100 turns each, of copper wire, wound upon a laminated iron core 14 (see Fig. 5). The 95 secondary windings of the transformer consist of four main turns 15, 16, 17 and 18. Each turn comprises a solid copper bar, bent to make one turn about the core 14. The upper ends of turns 15 and 17 are connected together by copper straps 19, the 100 lower ends of turns 16 and 18 are connected

together by copper straps 20, the upper end of turn 16 is connected to the lower end of turn 15 by copper straps 21, and the upper end of turn 18 is connected to the lower end 5 of turn 17 by copper straps 22. Bolted between the straps 19 are two sets of copper strap conductors 23 and 24, one-half of the straps 23 being bolted to the underneath side of one of the heads 6, and the other 10 half of the straps 23 being bolted to the top of the head 6, as clearly indicated in Fig. 1. Likewise, one-half of the straps 24 are bolted to the underneath side of the other head 6, and the other half of straps 24 are 15 bolted to the upper side of the other head 6, so that each head 6 is electrically connected to the upper ends of turns 15 and 17 through flexible connections. Bolted between the straps 20 are two sets of flexible 20 electric strap conductors 25 and 26, which are similarly bolted to the lower head 3, half being bolted to the underneath side of said head, and half being bolted thereto on the upper ledge of the head, as clearly 25 indicated in Fig. 1.

I also provide two extra secondary turns on the transformer, these turns being indicated at 27 and 28 (see Fig. 5). The turn 27 lies adjacent the turn 15 and is in electric contact therewith substantially over its 30 whole length. The turn 28 lies adjacent the turn 16, but is insulated therefrom by insulating material 29. The upper end of turn 27 is electrically connected to the upper end 35 of turn 28 by copper connecting straps 30. The lower end of turn 27 is connected to the lower end of turn 28 by connecting straps 31.

Surrounding the primary and secondary 40 windings is a laminated magnetic structure of soft iron 32, the shape of the laminations being shown in Fig. 5. In this figure, the shape of the laminations of the core structure 14 is also shown.

45 The ends of the primary turns are brought out from the primary coils to a connection box 33.

Pivoted to a cross-bar 34 (see Fig. 2) are two sets of arms 35 and 36. Back of the 50 said arms 35 is a wedge-shaped member 37, and back of the arms 36 is a wedge-shaped member 38, the members 37 and 38 being connected to the upper end of the arms 39 and 40, pivoted at 41 (see Fig. 2) and connected to lever arms 43 and 44, respectively, 55 so that, upon depressing the lever arm 43 or 44, the wedge-shaped member connected thereto will be forced between the inner ends of the arm 35 or 36 and cause the outer ends of these arms to approach one another 60 and engage the rivet 8 intermediate its ends, so as to make an electrical contact with the rivet intermediate its ends.

Bolted between the conducting straps 31 65 is a set of copper connecting straps 45,

divided into four groups, the outer end of each group being secured to make electrical connection with the inner end of one of the arms 35 and 36, respectively (see Figs. 1 and 2).

70

Any suitable connections 46 may be made to the ends of the lever arms 43 and 44, so that these arms may be depressed to cause the arms 35 and 36 to electrically engage the rivets therebetween, and likewise any 75 suitable means may be provided to cause the arms 43 and 44 to be retained in their depressed condition, so that the arms 35 and 36 will continue to engage their respective rivets during the heating thereof.

80

In operation, the rivets are placed between the heads 3 and 6, and the head 6 lowered thereon so as to hold the rivets therebetween under pressure. In the machine shown, the pressure is about eight pounds.

85

Assuming the transformer to be energized, current then passes from the secondary terminals through the heads 3 and 6 and through the rivet, causing the rivet to be heated from its flat end down; that is, it becomes hottest at its flat end and the rivet gradually becomes softened from its flat end downwardly or toward its head.

90

I find that the successful heating of rivets by electric current depends on maintenance 95 of certain conditions of voltage applied, and ratio between contact resistance and effective impedance in the rivet such as is found in the operation of the apparatus as above described.

90

The heating of the rivet is caused 100 by liberation of heat energy due to the opposition to the current. This opposition may be divided into two classes, that due to the contact resistance between the contact heads and the ends of the rivet and that due 105 to the effective impedance in the rivet which may consist of ohmic resistance, hysteresis losses, eddy current losses, inductance and skin effect losses.

100

These vary materially with the shape and size of the rivet and the 110 material from which it is made, and the nature of the current employed. In the apparatus described the contact resistance between the contacts and the ends of the rivet is such that the upper or flat end of the 115 rivet heats faster than the shank or middle portion of the rivet. This appears to be due to a relatively large amount of heat liberated at this end at the point of contact, by the current overcoming the contact resistance.

110

In this manner the heat is concentrated where it is needed most so that the final heating of the rivet is accomplished in a minimum time and with a minimum 120 consumption of energy.

120

However, this is perhaps not the most important feature, because, if the end of the rivet is melted or burned by this so-called concentration of heat, it is not suited to be afterward inserted in the hole in the 130

work because of the damaged end. This burning of the rivet is the local melting or liquefying of the rivet at the end of the rivet adjacent the contact. Burned rivets 5 are thrown away as scrap and even by the old methods of heating by coal or oil flame this loss is very large. I have found, however, that by using a relatively low voltage 10 this burning of rivets can be entirely eliminated without material loss in time in completing the heating of the rivets. If an excessive voltage is used, so much heat is generated at the contact that it can not be conducted into the body of the rivet fast 15 enough to prevent local overheating and burning of the rivet at the ends. To prevent burning with the apparatus described I may use an applied voltage of about 2 volts or slightly less. However, the highest voltage 20 which will not burn depends not only upon the size, shape and material of the rivet, and nature of the current but also upon the speed with which the contact heads conduct the heat away from the end of the rivet 25 and the pressure applied. I find, however, that according to the preferred form of the invention it is best to use below six volts.

But even though a relatively low voltage be applied, sufficient to prevent burning during the major portion of the heating, such voltage if applied at the start, might, due to the very low initial resistance of the rivet or bar, when cold, cause an excessive current to flow initially which would cause burning or splattering of molten metal at the beginning of the heating operation. To overcome this I provide an apparatus with a markedly drooping characteristic, so that if excessive current tends to flow due to the practical short circuiting of the secondary, the voltage will be reduced to a point where such splattering or burning is substantially eliminated. As the rivet or bar becomes heated and its 35 ohmic resistance increases the applied voltage will automatically increase in order that the article may be heated quickly, but the voltage at all times being kept below that which would cause burning.

60 The apparatus as a whole may be given a markedly drooping characteristic many ways as will be apparent to those skilled in the art, but I prefer to do it by providing the transformer, which is substantially iron clad and has a substantially complete iron magnetic circuit for efficiency, with a gap or gaps 60 in the magnetic circuit. In the arrangement the gaps 60 comprise air spaces filled with shellac. It will be understood that by suitable adjustment of conditions the effective internal impedance in the rivet and the contact resistances may be such that all parts of the rivet will heat up 65 equally fast or the center will heat up fastest, but the heating of the end fastest has the important advantage that the rivet is heated sufficiently for practical purposes in very much less time and with the consumption of much less energy, considerations which are of great importance, speed 70 being an especially important factor in present day commercial operations.

If a long rivet is being heated, it is desirable to make use of the third contact device or devices 35 and 36, in which case lever arm 43 is depressed, causing extra current, generated in the secondary turns 27 and 28, to be passed through the upper end portion of the rivet, so as to more quickly heat that portion of the rivet which is desired to be heated 80 and without burning the rivet,—that is, causing it to become too soft at the end that is to be upset later.

Suitable switching apparatus is provided, as shown in Fig. 6, whereby the number of 85 turns of primary windings may be varied,—that is, some of the turns may be cut out. For that purpose, a switch 50 is provided, adapted to make contact with contact 51, if all 300 turns are desired to be in circuit. 90 When the switch is thrown to contact 52, only 275 turns will be in circuit, and when thrown to contact 53, only 200 turns will be in circuit, the supply mains being connected, one to the switch 50 and the other to contact 95 54.

In the apparatus particularly illustrated in the drawings, I prefer to apply 220 volts at 60 cycles across the primary and to have the transformer so wound that about 3 amperes will flow in the primary when the secondary is open-circuited.

It will be noted that the four main secondary turns are connected in pairs,—two pairs in parallel, and two pairs in series.

When heating rivets $\frac{1}{4}$ inch in diameter by 1 inch long I preferably use the 300 turns of primary windings, and when so connected the calculated voltage on the secondary with the secondary open-circuited is about 1.4 110 volts.

With rivets $\frac{3}{8}$ inch diameter by $1\frac{1}{4}$ inches long, I preferably cut out part of the primary turns, so as to use only 275 primary turns, thus producing a calculated open-circuit secondary voltage of about 1.6 volts.

When heating rivets $\frac{3}{8}$ inch in diameter by $2\frac{1}{2}$ inches long, I preferably use about 200 turns in the primary and a calculated open-circuit secondary voltage of about 2 volts.

If a $\frac{1}{2}$ inch diameter by 3 inches long rivet is being heated, I preferably increase the open-circuit secondary voltage to about 2.5 volts, and if a $\frac{1}{2}$ inch diameter by $4\frac{1}{2}$ inches long rivet is being heated, I preferably increase the calculated secondary voltage to about 3.5 volts.

While by changing contact, impedance and current conditions greater voltages may be used without burning the rivets or bolt 130

blanks I preferably keep the applied voltage during heating under about $5\frac{1}{2}$ or 6 volts. Thus, the transformer should be so designed and wound or the source of electric current be so selected and connected as to send a current through the heads and rivet of such size as to heat the rivet soft the required distance without burning the end of the rivet.

With the above apparatus, I am enabled to heat rivets in from 3 to 60 seconds without burning.

While I prefer to use alternating current as energizing means, certain of my improvements may be found advantageous in case a direct current is used.

It is not necessary, to the broader aspects of my invention, that the apparatus be provided with two heads 6, but I find that if a plurality of heads 6, with coöperating head 20 or heads 3, is provided, supplied from the same source or transformer, and in parallel a plurality of rivets may be heated simultaneously. I find that, even although such plurality of rivets may be inserted simultaneously, one will always become heated before the other, so that the operator may insert and remove the rivets alternately, and thus greatly increase the speed with which rivets may be heated by the apparatus.

30 As shown in the drawings, only one head 3 is provided, but this is equivalent to two heads, as one portion coöperates with one head 6 and the other portion coöperates with the other head 6.

35 Since the third contact device 35 is connected to secondary windings on the transformer, which embrace only two turns in parallel, the voltage applied between the contact devices 35 and 36 and the head 6 40 will be about half of the voltage applied between the heads 6 and 3.

It will be noted that the other or upper terminal of the secondary windings 27 and 28 are common with the upper terminal of 45 the winding 15 and connections 23.

While I have described my improvements in great detail and in respect to an apparatus for carrying them out in one form, I do not desire to be limited to such details, 50 since many changes and modifications may be made and the invention embodied in widely differing forms without departing from the spirit and scope of the invention in its broader aspects. I desire to cover all 55 forms and methods coming within the language of the appended claims.

What I claim is:—

1. An apparatus of the class described having in combination a contact adapted to 60 make contact with the flat end of a rivet, bar or other article, a second contact adapted to make contact with the rivet, bar or similar article, and a transformer having a low potential secondary with its terminals 65 connected to said contacts respectively, said

transformer having a substantially complete iron magnetic circuit (but with a gap or gaps therein) to give the transformer a markedly drooping characteristic to prevent the flow of excessive current when the 70 rivet, bar or other article is first placed in circuit.

2. An apparatus of the class described having in combination a contact adapted to make contact with the flat end of a rivet, 75 bar or other article, a second contact adapted to make contact with the rivet, bar or similar article, and a transformer having a low potential secondary with its terminals connected to said contacts respectively, said 80 transformer having a substantially complete iron magnetic circuit and a markedly drooping characteristic to prevent the flow of excessive current through the rivet, bar or other article.

85

3. An apparatus of the class described having in combination a contact with a flat face adapted to make contact with the flat end of a rivet, bar or similar article, a second contact adapted to make contact with the rivet, bar or similar article, and a transformer with its secondary connected to said contacts respectively, the apparatus having a markedly drooping characteristic to prevent the flow of excessive current when the 95 impedance of the rivet, bar or other article is relatively low.

90

4. An apparatus of the class described having in combination a contact of relatively soft metal with a flat face adapted 100 to make contact with the flat end of a rivet, bar or other article, a second contact adapted to make contact with the rivet, bar or similar article, and a transformer with its secondary connected to said contacts respectively, 105 said transformer having a substantially closed iron magnetic circuit and the apparatus having a markedly drooping characteristic to prevent the flow of excessive current when the rivet, bar or other article is first placed in circuit.

110

5. In an electric heating apparatus of the class described, the combination of two electrical contact heads, one of which is movable with respect to the other, and a transformer having its secondary connected to said heads, said transformer having a relatively short gap or gaps in its magnetic path to prevent an excessive current when the secondary is substantially short circuited.

115

6. The combination of two contacts for making electrical connections with rivets, bars or other articles, and a transformer with its secondary terminals connected to 125 said contacts respectively, the apparatus having a markedly drooping characteristic to prevent the flow of excessive current through the rivets, bars or other articles.

120

7. An apparatus of the class described 130

- having in combination two contacts for making electrical connections with a rivet, bar or other article, and a transformer with its secondary terminals connected to said contacts respectively, said transformer having a substantially complete iron magnetic circuit and the apparatus having a markedly drooping characteristic to prevent the flow of excessive current when the rivet, bar or other article is first placed in circuit. 40
8. The combination of two contacts for making electrical connections with rivets, bars or other articles, and a transformer with its secondary terminals connected to said contacts respectively, said transformer having a substantially complete iron magnetic circuit but with a gap or gaps therein to give the apparatus a markedly drooping characteristic to prevent the flow of excessive current when the rivets, bars or other articles are first placed in circuit. 45
9. An apparatus of the class described having in combination two contacts for making electrical connections with a rivet, bar or other article, and a substantially iron clad transformer with its secondary terminals connected to said contacts respectively, said apparatus having a markedly drooping characteristic to prevent the flow of excessive current when the rivet, bar or other article is first placed in circuit. 50
10. An apparatus of the class described having in combination a contact with a flat face adapted to make electrical contact with the end of a bar, rivet or other article, a second contact also adapted to make electrical contact with the bar, rivet or other article, and a substantially iron clad transformer, having a substantially complete iron magnetic circuit, with its low potential secondary terminals connected to said contacts respectively, said transformer having a gap or gaps in its magnetic circuit to give the transformer a markedly drooping characteristic to prevent the flow of excessive current when the rivet, bar or other article is first placed in circuit. 55
11. An apparatus of the class described having in combination a transformer, a plurality of contacts for making electrical connections with a plurality of rivets, bars or other articles respectively to connect the rivets bars or other articles to the transformer terminals, but with the rivets, bars or other articles in parallel with one another, said apparatus having a markedly drooping characteristic to prevent the flow of excessive current through the rivets, bars or other articles when their impedance is relatively low. 60
12. An apparatus of the class described having in combination, a transformer, means for electrically connecting the transformer to a bar, rivet or other article to heat the same, said means including an electric contact device for gripping the bar or other article intermediate its ends, and said apparatus having a markedly drooping characteristic to prevent the flow of excessive current through the rivet, bar or other article when it is first placed in circuit. 65
